(57) **CLAIM**

The ornamental design for a wireless earbud with package box, as shown and described.

DESCRIPTION

FIG. 1 is a front perspective view of the earbud portion of a wireless earbud with package box showing the new design, shown separately to show aspects of the design that are not visible when combined;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and

FIG. 8 is a bottom plan view thereof.

FIG. 9 is a front perspective view of the package box portion of the wireless earbud with package box, shown separately to show aspects of the design that are not visible when combined;

FIG. 10 is a rear perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof; and

FIG. 16 is a bottom plan view thereof.

FIG. 17 is a perspective view of the wireless earbud with package box shown with all aspects of the design combined; and,

FIG. 18 is a perspective view of the wireless earbud with package box, shown in a closed state.

The broken lines in the figures depict portions of the wireless earbud with package box that form no part of the claimed design.

1 Claim, 18 Drawing Sheets
